UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

SHUTTLE.

964,708.

Specification of Letters Patent. Patented July 19, 1910.

Original application filed November 12, 1907, Serial No. 401,831. Divided and this application filed July 27, 1908, Serial No. 445,589. Renewed February 10, 1910. Serial No. 543,189.

To all whom it may concern:

Be it known that I, EDWARD S. STIMPSON, of Hopedale, in the county of Worcester, State of Massachusetts, have invented certain new and useful Improvements in Shuttles, of which the following is a specification.

The improved shuttle which constitutes the present invention is particularly intended for use in the automatic weft-replenishing loom described in application for United States Letters Patent, Serial No. 401,831, filed November 12, 1907, of which the present application is a division. Said co-pending application, No. 401,831, sets forth mechanism for insuring the proper location of the shuttle when a fresh bobbin or other weft-carrier is to be automatically supplied thereto, said mechanism comprising a shuttle placer which enters the shuttle and moves it to the desired position. The shuttle is especially constructed to coöperate with the shuttle placer, and it is this particular construction of the shuttle which constitutes the subject matter of this divisional application.

The improved shuttle is illustrated in the accompanying drawings, in which—

Figure 1 is a plan view of the end of the shuttle which is equipped with the weft-carrier jaws. Fig. 2 is a longitudinal vertical section of the same end of the shuttle. Fig. 3 is a perspective view of the shuttle abutment against which the shuttle placer acts.

The shuttle B is provided with the usual resilient weft-carrier holding jaws a, a. The shuttle has an abutment J which is adapted to be encountered by the shuttle placer. This abutment is located wholly within the shuttle chamber and has a vertical face d which extends the entire width of the shuttle

chamber. The abutment is part of a piece of sheet metal pressed into suitable shape for secure attachment to the shuttle body, no part of the same extending beyond the outer boundaries of the shuttle. Beneath the abutment proper there is a horizontal ledge e and a vertical wall f, which is located between the shuttle jaws a and nearer the middle of the shuttle than the face d of the abutment. The wall f is close to the butt end of the weft-carrier held by the jaws. This wall is distant from the abutment face to the extent of the ledge e, thus affording a space between the abutment face and the butt end of the weft-carrier for the action of the shuttle placer. The width of the abutment allows for such movement of the lay as takes place during the action of the shuttle-placer.

I claim—

1. A shuttle for an automatic weft-replenishing loom having an interior abutment adapted to be encountered by a shuttle placer, said abutment extending crosswise of the shuttle-chamber and substantially the full width of said chamber.

2. A shuttle for an automatic weft-replenishing loom, having weft-carrier holding jaws at one end and interior abutment adapted to be encountered by a shuttle placer and a vertical wall between the shuttle jaws, said wall being nearer the middle of the shuttle than the abutment.

In witness whereof, I have hereunto signed my name in the presence of two subscribing witnesses.

EDWARD S. STIMPSON.
